UNITED STATES PATENT OFFICE.

JOSEPH J. SCHOLFIELD, OF PROVIDENCE, RHODE ISLAND.

MACHINE FOR PRINTING LINEAR MEASUREMENTS UPON FABRICS.

SPECIFICATION forming part of Letters Patent No. 230,441, dated July 27, 1880.

Application filed January 15, 1880.

To all whom it may concern:

Be it known that I, JOSEPH J. SCHOLFIELD, of Providence, in the State of Rhode Island, have invented an Improved Machine for Measuring, Registering, and Packaging Fabrics, of which the following is a specification.

My invention relates to an improved machine for graduating and registering the linear measurement of textile and other fabrics and for rolling the graduated and registered fabrics into suitable convenient packages for transportation or sale.

It also relates to an improved method of measuring elastic fabrics, which consists in measuring and marking upon the fabric a certain standard linear unit, and adjusting the movement of an indicating, graduating, or registering mechanism to compensate for the resulting stretch of the fabric when placed under tension in the machine, as determined by comparison with the fixed original standard unit of measurement.

The object of this invention is, first, to correctly measure in the same machine fabrics having different degrees of elasticity; second, to automatically affix graduated numerals or other marks upon the surface of the material, to indicate the number of units of linear measurement contained in the whole web or a portion thereof; third, to fold a fabric longitudinally; and fourth, to roll an elastic fabric into a convenient package under an approximately uniform tension, thus preventing injurious distortion of the graduated and registered measurement in the resulting roll or bolt.

Figure 1 is a plan view of the machine. Fig. 2 is a longitudinal elevation, showing the working side. Fig. 3 is a longitudinal elevation, showing the driving side. Fig. 4 is a transverse section of the machine, taken in a vertical plane passing through the axis of the driving-shaft. Fig. 5 is a front elevation of the wheel employed for graduating and registering the linear measurement and a longitudinal section of the inking apparatus and pivoted frame for supporting the wheel. Fig. 6 represents the back side of the wheel employed for graduating and registering the linear measurement. Fig. 7 is a section taken in a vertical plane passing longitudinally through the axis of the wheel employed for graduating and

registering the linear measurement. Fig. 8 is a plan view of a portion of the mechanism for actuating the type-wheels, taken when in the position shown in the side view, Fig. 5. Fig. 9 represents a section taken in a plane indicated by the dotted line in Fig. 8. Fig. 10 is a transverse section of the spring mechanism for throwing the type-wheels back to their zero-point, taken in a plane indicated by dotted line in Fig. 5. Fig. 11 is a section of the same, taken at right angles to the axis of the spring. Fig. 12 is a face view of the cam for producing the forward movement of the type-wheels. Fig. 13 is an edge view of the same. Fig. 14 is an inner-face view of the hub of the gear for imparting the proper movement to the wheel employed for graduating and registering the linear measurement. Fig. 15 is a sectional view of the same as indicated by dotted line in Fig. 14. Fig. 16 is a side view of the end of the sliding catch-sleeve for securing a suitable gear to the shaft of the wheel employed for graduating and registering the linear measurement. Fig. 17 is a face view, and Fig. 18 an edge view, of a gear with a single tooth for operating the type-wheel for tens. Fig. 19 is a face view, and Fig. 20 an edge view, of the type-wheel for units. Fig. 21 is a face view, and Fig. 22 an edge view, of the type-wheel for tens, showing also its attached gear of ten teeth. Fig. 23 is a face view of the cam for automatically raising the wheel employed for graduating and registering the linear measurement upon the complete measurement of the web. Fig. 24 is a partial end elevation, showing the location and construction of the folding mechanism. Fig. 25 is a plan view of the scale for measuring the resulting stretch of the fabric when subjected to tension. Fig. 26 is an end view of the pivoted folding mechanism when opened out to receive the forward end of the web. Fig. 27 is a partial end elevation, showing the mechanism for rolling the fabric into a package. Fig. 28 is a face view, Fig. 29 an edge view, and Fig. 30 an end view, of the flat mandrel employed for the purpose of rolling the fabric upon a board to form a bolt. Fig. 31 is a face view, and Fig. 32 an edge view, of the loose clamp-piece for suitably holding one end of the board. Fig. 33 represents a side view of

the square mandrel for winding the fabric into a roll. Fig. 34 is a longitudinal section of the mechanism employed for driving the mandrel. Fig. 35 is an end view of the mandrel-driving shaft, showing the grooved face-plate for holding the flat mandrel. Fig. 36 is a sectional view of the friction-wheel for driving the mandrel, also showing the friction-clamp and its lining of woolen or felted fabric. Fig. 37 is a longitudinal section of the loose socket-center for holding and releasing the mandrel. Fig. 38 is a side elevation of a portion of the sleeve in which the socket-center revolves, showing also the inclined cam-groove for moving the center longitudinally, as desired. Fig. 39 is a vertical section of the fixed bearing for holding the socket-center, also showing the fixed pin and slotted sleeve for producing the required forward and backward movement. Fig. 40 is an end view of the socket-center. Fig. 41 is a plan view of the machine, with the registering portion removed, illustrating the method of folding the web longitudinally and packaging. Fig. 42 is a sectional view of the same, taken in a vertical plane at the front edge of the web. Fig. 43 is a plan view of machine, with the registering portion removed, illustrating the method of attaining the correct measurement of an elastic fabric when placed under tension from the data of a previously-measured standard linear unit. Fig. 44 is a sectional view of the same, taken in a vertical plane at the front edge of the web. Fig. 45 is a partial vertical section, showing an edge view of the link for connecting the ends of two similar webs, and also showing the attached cam-piece for automatically raising the graduating and registering mechanism from the web. Fig. 46 is a plan view of the link-piece for connecting the ends of the webs. Fig. 47 is a plan view of the table and measuring-bar for imprinting the standard linear unit upon the edge of the web, as a guide to the subsequent correct adjustment of the graduating and registering mechanism.

In the accompanying drawings, (see Figs. 41 and 42,) A represents a web of wide goods rolled upon a spool, B, which is held in an upright position by means of the step *a* and upper bearing, *b*. The web A passes from the spool B around the upright roll B', and thence to the folder C, which is attached to the adjustable table D, located in a horizontal plane passing through the middle of the web A, as held upon the spool B, and consists of a bed-piece, *c*, made in any desirable width, a tongue, *d*, adjustably held in the screw-clamp *e*, which is pivoted to the bed *c* at the points *e' e'*, and the top piece, *f*, pivoted to the bed *c* at the points *f' f'*, and slotted at *g*, in order to suitably hold the adjustable guide *h* for operating upon the folded edge of the fabric.

The adjustable table D is pivoted to the frame E at the points *d' d'*, and is held at a suitable inclination lengthwise of the web by means of the pawls *j j* and the notches *kk* under the table. The table D may also be inclined crosswise of

the web by means of adjusting-screws *c' c'*, one above and one below the pivot *d'*, as shown in elevation, Fig. 2.

The tension-roll F, located at a short distance in advance of, and above the plane of, the table, may be slightly frictioned by suitable means, in order to arrest the motion of the roll at the instant of stopping the movement of the measuring mechanism and to suitably augment the friction of the web upon the surface of the tension-roll F', both rolls being preferably made as light as practicable and covered with vulcanized india-rubber or other suitable frictional material.

The roll F' is provided at one end with the friction-wheel *f'*, to be operated upon adjustably by means of the weighted lever G, pivoted to the frame E at the point *g'*, and provided upon the upper surface of its short arm with an attached friction-facing, H, preferably made of woolen or felted fabric, which, by producing a uniform degree of friction, tends to secure a correspondingly uniform tension in the web, which is an indispensable requirement to correct measurement and registration.

Upon each side, at the top of the frame E, are placed the vertically-slotted standards I I' and I² I³, which constitute the journal-bearings for the pressure feed-rolls J J' and J² J³, the lower rolls, J and J², being connectedly driven by means of the gear K upon the shaft of the intermediate roll, J⁴, gear K' and K², upon the shafts of the rolls J and J² respectively, and the loose intermediate gears, K³ K³, all of equal size. The upper rolls, J' and J³, are made comparatively heavy, and are turned in their bearings by frictional contact with the upper surface of the web, or with the surface of the lower rolls, J J², which are preferably covered with vulcanized india-rubber.

The above-described upper and lower feed-rolls may, however, be geared together, so as to be strictly positive and equal in their movement, if preferred.

The upper ends of the standards I I' and I² I³ are connected by the loosely-fitted rods G' G², held in position by the inside collars, g' g².

The rectangular frame L, provided with a projecting arm, L', which rests upon a cam, L², secured to the loose rod G², is pivoted to the rod G', and is provided upon its under side with the journal-boxes l l, to receive the shaft m, upon which is rigidly secured the wheel M, employed for graduating and registering the linear measurement of the fabric, being provided upon the exterior of its rim with the studs b' b² b³, for imprinting graduations of fractional parts of the unit, and upon the inner side of its rim with the transversely-arranged type-wheels m' and m², adjoining each other and provided upon their peripheries with engraved numeral figures, to imprint upon the surface of the fabric the units and tens, as required, to indicate the proper number of yards or other linear units of measurement in the web. The wheels m' m² are placed loosely

upon a pin, n , passing through the standards n^1 and n^2 , connected to each other by means of the back plate, n^3 , which is securely attached to the flat plate of the wheel M , so as to cause the type-faces of the wheels m^1 m^2 to project a suitable distance beyond the outer periphery of the wheel M .

Upon the hub of the loose unit-wheel m^1 is rigidly secured the gear o , provided with any desirable number of teeth, and engaging with a similar gear, o' , attached to the shaft p ; and upon the hub of the tens-wheel m^2 is rigidly secured the gear o^2 , provided with ten teeth, which are made concave upon their outer ends to secure the pitch-line locking-surface of the single-toothed gear o^3 , secured to the shaft p . Thus, upon a complete revolution of the unit-wheel m^1 the tens-wheel m^2 will be thrown forward one-tenth of a revolution, and there be retained by the interlocking surfaces of the gears o^2 and o^3 until the wheel m^1 has again completed a revolution.

Upon one end of the shaft p is securely fastened the bevel-gear pinion o^4 , engaging with the bevel gear o^5 , turning loosely on the stud p^2 , attached to the back plate, n^3 . To the hub of the gear o^5 is securely attached the scroll-spring q , inclosed in a fixed case, q' , and provided with an attached friction-ring, q^2 , whereby, when the spring has been wound up to its extreme tension, the consequent slipping of the friction-ring around the inner side of the rim of the case q' will prevent the breaking of the spring or injury to other parts of the positively-driven mechanism. The spring q serves to automatically return the type-wheels m^1 and m^2 to the zero-point whenever the graduation and registration of the web has been completed.

At the opposite end of the shaft p is rigidly secured the gear o^6 , engaging with the gear o^7 , attached to the shaft p' , which is held in the forked journal-box r , pivoted at the points r' to the fixed standard s , so that the gear o^6 , provided with ten teeth and rigidly secured to the outer end of the shaft p' , may be disengaged from the fixed cam t by the action of the spring r^2 , without at the same time disengaging the gears o^6 and o^7 .

When the gear o^8 of ten teeth is placed in engagement with the fixed cam t , and the wheel M revolved in the proper direction, the unit-wheel m^1 will be moved progressively forward through a space equal to one-tenth of its periphery, and thus increasing one unit at each revolution of the wheel M , and for every ten units of movement imparted to the unit-wheel m^1 a single ten-unit movement will be imparted to the tens-wheel m^2 , and upon raising the gear o^8 from its engagement with the cam t the action of the spring q will immediately return the wheels m^1 and m^2 to the zero-point, as indicated by the pin u upon the hub of the gear o^2 , and which strikes against the end of the pawl u' , held in contact with the hub of the gear by means of the spring u^2 .

The cam t rests loosely upon the hub of the

wheel M , and is fixedly attached to a convenient portion of the frame L in order to prevent the cam from revolving with the wheel. 70 One-half of the periphery of the cam is cut into a screw-thread having a pitch double that corresponding to the teeth of the gear, the remaining half of the periphery being cut in a plane directly at right angles to the axis 75 of the cam, so that during one-half of the revolution of the wheel M the gear o^8 will be moved through the space of one tooth, or one-tenth of a complete revolution, and will continue at rest during the remaining half of the 80 revolution of the wheel.

At one side of the journal-box r is attached a dependent arm, r^3 , which engages with the beveled sleeve v , provided with the ears v' , and sliding loosely upon the hub of the fixed 85 cam t .

An inclined link-connection, w , is made from the ears v' of the beveled sleeve to the fixed standard x , attached to the frame E , so that when the outer end of the frame L is raised 90 by means of the cam L^2 , or otherwise, the link w will cause the sleeve v to be drawn back, and thus allow the spring r^2 to withdraw the gear o^8 from its previous positive engagement with the cam t , and upon again lowering the outer end of the frame L , by turning back the cam L^2 , the resulting downward movement of the sleeve v will cause it to be thrown forward by the action of the inclined link w , so that the beveled face of the sleeve, acting 95 upon the dependent arm r^3 , will cause the gear o^8 to be again thrown into positively-held engagement with the cam t . 100

Upon the outer end of the arm L' is pivoted the gravitating latch y , extending inwardly 105 between the guiding-ears y' , and serving, in conjunction with the stop y^2 , fixedly attached to the plate of the wheel M , to prevent said wheel from making more than one revolution in a backward direction. 110

The scroll-spring Z is attached at one end to the wheel M , and at the opposite end to the hub of the friction-wheel Z' , made to fit loosely on the shaft m , and held in the adjustable friction-clamp Z^2 , which is prevented from moving 115 with the friction-wheel by means of a suitable connection made to the frame L , so that upon starting the wheel M in the proper direction to wind up the spring Z the friction-wheel Z' will remain stationary until the tension of the 120 spring has become fully equal to the frictional resistance produced by the clamp Z^2 , and the continued movement of the wheel M will then operate to revolve the friction-wheel Z' against the frictional resistance of the clamp. 125

The gear N is removably attached to the outer end of the shaft m , and is held from turning upon the shaft by means of a sliding catch-sleeve, l' , which is also prevented from turning on the shaft by means of a slot, l^2 , and pin l^3 , and thrown forward in the direction of the axis of the shaft by means of the spiral spring l^4 , which encircles the shaft within the inclosing-sleeve. 130

The hub of the gear N is provided upon its inner face with an inclined notch, b^5 , to receive the catch-pin b^6 , attached to the face of the sleeve.

5 The inclined notch b^5 and the catch-pin b^6 , held against the face of the hub by means of the spring b^4 , will allow the gear N to be turned in a backward direction without imparting movement to the wheel M, thus preventing 10 breakage in case the machine is inadvertently turned backward after the wheel M has been brought to a stop by the action of the latch y.

Whenever the frame L is placed in its lower position the gear N will engage with the gear 15 N', which is removably attached to the shaft j' of the intermediate roll, J⁴; but upon raising the frame L so that the gears N and N' become disengaged, the tension of the spring Z, operating against the friction of the clamp Z², 20 will cause the wheel M to turn backward until the stop y² comes in contact with the end of the latch y, thus automatically bringing the wheel M, balanced by the weight m³, in all cases to the proper fixed position for commencing the registration of a web. Upon the 25 shaft j', at the end of the intermediate roll, J⁴, is loosely fitted the short impression-roll J⁵, made to press the web against the type-wheels, so as to make an imprint upon the selvage.

30 The inking apparatus L³ is adjustably and removably attached to the platform L⁴, located at the pivoted end of the frame L, by means of a screw, l^1 , and slot l², and consists of an ink-reservoir, k⁵, an ink-feeding roll, k¹, a vibrating ink-distributing roll, k², operated from side to side by means of the cam k³, the inking-rolls k⁴ k⁴, driving-gears k⁵ k⁶, and wheel k⁶, by the frictional contact of which with the periphery of the wheel M a proper rotary movement will be imparted to the inking-rolls.

35 The inking-rolls k⁴ k⁴ should be driven at about the same surface-speed as that of the printing-type attached to the wheel M.

To the shipper-fork O, pivoted to the journal-bearing R' at the point i², is jointed the 40 sliding shipper-rod O', operated, by means of the spring O², to throw the belt from the tight to the loose pulley, and held in proper position for action by means of a notch in the shipper-rod. Connection is made to the spring 45 shipper-rod O' from the frame L by means of the hooked link L⁵. Upon lifting the shipper-rod so that the holding-notch is released from its catch the action of the spring O² will cause 50 the belt to be shifted from the tight to the loose pulley, and thus stop the motion of the machine.

To the inner side of the pivoted frame L is attached the arm M', to the lower end of which 55 is secured the loose cam M², which serves, in conjunction with the cam-rib M³, attached to the web-connecting link-piece N², to automatically raise the frame L and its attached mechanism, thus causing the automatic readjustment of the 60 type-wheels to their zero-point upon the completion of the measurement and graduation of

the forward web, preparatory to the continued measurement and graduation of the succeeding web.

The roll J⁴ is connected with the driving-shaft P by means of the pinion P', attached to the driving-shaft, and the gear P², attached to the shaft of the roll J⁴. The driving-pulley P³, fixedly attached to the shaft P, is connected by belt with the pulley Q fitting loosely upon the shaft R, held in the bearings R' and R², attached to the frame E. Between the two bearings R' and R², and adjoining the pulley Q, is placed the friction-wheel S, fixedly attached to the shaft R, and provided with a friction-clamp formed in two parts, S' S', connected by the screws s' s', provided under their heads with the springs s² s², whereby an adjustable yielding pressure may be produced against the periphery of the friction-wheel. 70 A pin, s³, attached to the side of the pulley Q, enters a hole or slot, s⁴, made in the projection t' upon one of the parts S' of the friction-clamp. The clamp S' S' should be lined with a woolen or felted fabric, s⁵, which will tend 75 to secure comparative uniformity in the frictional results produced.

The amount of power transmitted to the shaft R may be varied and controlled by adjusting the pressure of the spring-clamp S' S' upon the periphery of the friction-wheel by means of the screws s' s', as desired. The inner end of the shaft R is provided with the socket-opening r¹, to receive the socket of the square tapering mandrel r⁶, (shown in Fig. 100 33,) and upon which the fabric is to be wound to form a roll. Upon the inner end of the shaft R is fixedly attached the friction-wheel R³, provided on its front face with the shallow grooves r⁵ r⁵, made eccentric to the axis of the 105 shaft, for the purpose of holding one end of the flat mandrel T, which is employed to wind the fabric around a board, p³, to form a bolt.

The friction-wheel R³ is provided upon its grooved periphery with a friction-strap, R⁴, lined with a woolen or felted fabric, s⁶, and attached at one end to the lug R⁵ and at the opposite end to the regulating-lever U, which is also pivoted to the lug R⁵. Upon the lever U is placed the sliding carriage U', provided 110 upon its upper edge with an upright stud, u³, for the purpose of holding a variable number of weights suited to produce the proper amount of frictional resistance upon the periphery of the wheel R³. Counterbalancing-weights are 115 also to be placed upon the upright stud u⁴, fixedly attached to the outer end of the lever U. The flat mandrel T, for rolling the fabric into a bolt upon a board, is held in proper position to be rotated by means of the swivel-shaft V, provided with a socket-opening, v', by 120 means of which the shaft V may be made to rotate within the sleeve V'. The shaft V is held within the sleeve V' by means of the shoulder v² and nut v³. The sleeve V' is provided with a fixed hand-wheel, V², and is operated forward and back within the bearing V³, 125

in order to either hold or release the mandrel T by means of a screw or cam-slot, v^4 , and pin v^5 .

The flat mandrel T is provided at one end 5 with a cross-piece, t^2 , having in the center of its outer edge a pyramidal socket, t^3 , made to fit the socket-opening of the shaft V.

The spurs t^4 t^4 extend inwardly from the head or cross piece t^2 , and serve to hold one 10 end of the board p^3 in place while rolling the fabric thereon, the opposite end of the board being similarly held by means of the loose sliding piece T', provided with the spurs t^5 t^5 .

To the rocking shaft W, held loosely in bearings attached to the frame E, is attached the 15 flat curved regulating-arm W', held up against the mandrel T by means of a spring placed upon the rocking shaft.

Motion is transmitted from the shaft W to 20 the sliding weighted carriage U' by means of the arm W², attached to the shaft W, the link W³, and the lever W⁴, pivoted at the point w⁵, and provided with a slotted opening, w⁶, at its upper end, to receive the pin or screw w⁷, 25 by means of which it is connected to the carriage.

The regulating-arm W will become depressed as the fabric is being wound upon the mandrel, which will cause the weighted carriage 30 U' to be brought gradually nearer to the fulcrum of the lever U, thus gradually diminishing the frictional resistance of the strap R⁴ upon the periphery of the wheel R³.

Through a hole in the standard I², just in 35 side of the rolls J² J³, is placed the pointer X, which is drawn back from the selvage of the web by means of the spring x¹ placed between the standard I² and the collar x².

At a distance from the pointer X equal to 40 one yard or other unit of measurement, or an exact fractional division of such unit, is placed the scale X', secured at right angles to the stem x³, and which is drawn back from the selvage of the web by means of the spring x⁴ 45 operating between the side of the frame E and a pin or collar, x⁵.

The edge of the scale X' may be graduated 50 into quarter inches or other suitable uniform linear divisions, the zero-point on the scale 55 commencing at the above-specified distance from the pointer X, with the graduations continued forward far enough to embrace within their scope the full amount of stretch properly imparted to the fabric between the pointer X 55 and the zero-point of the scale X', in order to cause the fabric to pass smoothly between the rolls J J' and J² J³.

The selvage-guide Y may be adjusted in its 60 position to act upon the edge of the fabric by means of the screw y³ and slot y⁴.

The pressure-plate w' is held loosely upon 65 two pins, w², and is located above the table w³, which supports the edge of the web. The pins w² serve, by pressing against the selvage of the web as it is held in the rolls J J' and J² J³, to properly adjust the position of the selvage relatively to the position of the type-

wheels m' m², so that the imprint of the type 70 may be made at the proper uniform distance from the edge of the web.

The pressure-plate w' is suitably held down to the upper surface of the web by means of the spring w⁴, attached to the supporting-standard.

Upon a platform or table, A', is hinged or 75 pivoted the bar B², provided at its ends with the studs b⁴ b⁵, set at a distance from each other equal to the distance between the end of the pointer X and the zero-point of the stretch-indicating scale X'.

The studs b⁴ b⁵, after being suitably inked upon their ends, serve to imprint a preliminary standard unit of measurement upon the edge of an elastic fabric, for the purpose of comparison in the machine with a like unit of 85 measurement, as indicated by the pointer X and the zero-point of the scale X', in order to determine the specific amount of stretch or elongation per standard unit of measurement resulting from the resistance of the tension- 90 rolls upon the surface of the web.

Suitable guiding lines or marks f² may be made upon the surface of the tension-rolls F F', and also upon either of the rolls J J' J² J³, for the purpose of guiding the insertion of the 95 forward end of the web into the machine, so that the edge of the web may, at its initial point for measurement, be properly arranged for continuous forward movement under the type-wheels and in the proper line for being rolled 100 with uniformity upon the packaging-mandrel.

Flexible aprons N³, made of canvas or other suitable material and provided with a series of hooks, h' h', may be employed to secure the proper tension at each extreme of the web being attached thereto, as shown in Figs. 43 and 44, which also illustrate the improved method of ascertaining the specific stretch or elongation of the fabric arising from the applied tension, in order to adjust the forward movement 110 of the graduating or registering mechanism with desirable certainty, so as to meet the requirement of the forcibly-lengthened condition of the fabric.

Several webs of the same quality may be 115 joined end to end by means of flexible link-pieces N², provided at each side with hooks h' h', and having attached to their upper surfaces a cam-rib, M², made of leather or other suitable flexible material, and the extreme webs of a 120 folded pile, A², may be provided with flexible leading and following aprons N³ N³, likewise attached to the web by means of hooks h' h'.

The forward end portion of the web at the top of the pile, prior to its insertion into the 125 machine, is to be placed upon a table, A', so that the longitudinal edge of the fabric may lie in a natural unstretched condition along the edge of the table, adjoining the hinged measuring-bar B². The studs b⁴ b⁵ upon the bar, having been first inked upon their ends, are to be brought over upon the web A, as shown in Fig. 47, thus imprinting upon the fabric a true 130 standard yard or other desirable unit of linear

- measurement, which is to be made exactly equal to the distance from the end of the pointer X to the zero-point of the scale X'. The end of the leading-apron N³ is then to be passed 5 around the tension-rolls F F' and between the rolls J J', and J² J³, and drawn forward by the action of the rolls upon the surface of the apron and the web, until the forward mark, a², or imprint of the stud b⁴ upon the web has 10 reached a point exactly opposite the end of the pointer X. Then the position of the mark a² or imprint of the stud b⁵ with regard to the zero-point c² of the scale X' will show upon inspection the exact changed or elongated condition 15 of the web resulting from the tension applied to the same by means of the frictioned rolls F F', in order to make the web run smoothly through the machine. If the mark a² falls back from the zero-point of the scale X' a distance 20 equal to one inch, then the proper and correct standard yard or other linear unit of measurement, as above imprinted upon the surface of the fabric, has been subjected to a stretch of one inch, requiring a corresponding 25 decrease in the speed of the wheel M, to which the graduating or registering devices are attached, in order to graduate or register the fabric correctly.
- A gear, N, and pinion N', with the proper 30 relative number of teeth, having been selected and placed upon their respective shafts, the machine may be started, and the graduation and registration of the fabric be proceeded with until the terminal end of the first web 35 has been reached, and at this point the cam-rib M³, attached to the link-piece N², by passing under the cam M², attached to the frame L, will cause the frame L and link L⁵ to be raised, as shown in Fig. 45, thus disengaging 40 the spring shipper-rod O' from its catch and causing the stoppage of the machine. The beveled sleeve v, being at the same time drawn back by the action of the inclined link w, allows the gear o⁶ to become disengaged from 45 the cam t, and the type-wheels m' m² to be returned to their zero-point by the action of the spring q, and the gear N, being at the same time disengaged from its pinion N', allows the wheel M to be thrown backward by means of 50 the spring Z to the initial starting-point for 55 the measurement of the succeeding web. The cam-rib M³, attached to the link-piece N², should be made of such a length, compared with the periphery of the cam M², as to allow the continued revolution of the machine to cause the type-wheels to be brought down upon the surface of the succeeding web at the proper initial point for the commencement of its graduation and registration.
- 60 If the rolls J J² are made just equal to twelve and one-half inches in circumference, and the wheel M calculated to graduate and register linear yards, then, for the measurement, graduation, and registration of inelastic fabrics, the gear N, with a pitch-circle of thirty-six inches circumference, may have one hundred

and forty-four teeth, and the pinion N', with a pitch-circle of twelve and one-half inches circumference, may have fifty teeth, the circumferential pitch of the teeth being one-fourth 70 of an inch in this case. Now if we preserve the same diameters and make three additional gears having one hundred and forty-five, one hundred and forty-six, and one hundred and forty-seven teeth, respectively, to run interchangeably with the former gears, and with three additional pinions having forty-nine, forty-eight, and forty-seven teeth, respectively, for the measurement of elastic fabrics, then the proper changes in the forward movement of 75 the wheel M can be readily effected for every quarter-inch stretch or elongation of the web from the zero-point of the scale X' to the extreme of three inches.

In measuring and packaging fabrics of double 80 width the webs may be successively joined to each other by means of two link-pieces placed side by side, with the dividing-line between them at the center of the width of the web, in order that the ready folding of the fabric may 85 not be interfered with. The joined webs, in an outspread condition, are rolled upon a spool, B, and held in an upright position, as shown in Figs. 41 and 42.

The web A is taken from the spool B around 90 the upright roll B', placed in line with the revolving type-wheels, so that the edges of the web may pass from the roll B' in a direct vertical plane under the type-wheels and graduating-points to the packaging-mandrel. 95

In order to insert the web A into the folder the top piece, f, and the tongue d are both turned back on their respective pivots, as shown in Fig. 26.

The lower edge of the web, as it comes from the spool B around the roll B', is to be brought against the lower selvage-guide, i, the tongue d to be thrown into position, and the remaining upper portion of the web folded upon it and inclosed by the top piece, f, so that the 105 upper edge of the web may rest against the upper selvage-guide, i', with the guide h held at about the thickness of the web from the end of the tongue d. The web is passed from the folder under the tension-roll F and down under 110 the tension-roll F', thence between the rolls J J' and over the tapes j² j², running upon the rolls J⁴ J⁶ J⁷, and between the rolls J² J³, to the packaging-mandrel T. The board p³, upon which the fabric is to be rolled, is placed 115 against the side of the mandrel and forced against the spurs t⁴ t⁵. The loose clamp-piece T' is then placed upon the mandrel and forced against the opposite end of the board, the penetrating-spurs t⁶ t⁷ serving to secure the board 120 p³ firmly to the mandrel, as shown in Fig. 27.

Having determined the extreme outer dimension of the bolt to be formed upon the board, the friction-clamp S' S' is to be adjusted 125 so that it will transmit to the mandrel, at the terminal portion of the bolt, sufficient power to produce the proper tension upon the fabric 130

in order to roll it compactly. This amount of power, however, would be much too great for the initial portion of the roll, owing to the increased leverage secured at the starting-point, 5 and in order to compensate for this increased leverage the lever U is weighted and the limit of the movement of the carriage U' so adjusted that at the starting-point of the roll or bolt the surplus power entering through the friction-clamp S' S', adjusted as above, may be absorbed by the fixed friction-strap R⁴, so that the actual pull upon the web, when firmly held, 10 may be made the same at both the initial and terminal portions of a roll or bolt by gradually moving the weighted carriage U' toward the fulcrum of the lever U.

The initial position of the carriage U' upon the lever U should be such that upon the completion of the roll the weighted carriage will 20 have been brought, by the action of the arm W¹, arm W², link W³, and lever W⁴, to a position near the fulcrum of the lever U, in which the counterbalancing-weights U³ will cause the removal of the previous tension upon the friction-strap R⁴, thus allowing the full power 25 transmitted by the friction-clamp S' S' to act upon the web.

The proper adjustment of the carriage U' in position upon the lever U in any case may be 30 made by changing the angular position of the arms W¹ and W² upon the shaft W relatively to each other.

The amount of stretch or elongation arising 35 from the friction of the tension-rolls may also be determined, before the web enters the machine, by first accurately weighing the amount of resistance encountered by a web, when the weight H', upon the lever G, is placed in a particular notch; then, if the preliminary standard unit of measurement is marked upon the edge of the web, so as to correctly represent the true yard required to be graduated or registered, and if a weight equal to the above-mentioned resistance of the tension-rolls is 45 properly applied to the end of the web, then the comparison of the marks a' a² of the above measurement with the original standard yard, by means of which the marks were made, will indicate, as before described, the proper change 50 of gears to be made in any case.

I claim as my invention—

1. In a machine for graduating or registering the linear measurement of fabrics, the combination of rolls for holding the fabric under a proper tension while being measured with a 55 graduating or registering mechanism the exterior marking or imprinting points of which have a positive rotary movement slower than the forward movement of the stretched surface of the fabric, substantially as described.

2. The combination of rolls for holding the fabric under a proper tension while being measured with a revolving graduating or registering mechanism having the exterior movement 65 of the marking or imprinting points made slower than the forward movement of the

stretched surface of the fabric by means of compensating-gears, substantially as described.

3. The combination of rolls for holding the fabric under a proper tension while being measured with a positively-driven graduating or registering mechanism and an impression-roll arranged loosely upon a revolving shaft through which the power for driving the graduating or registering mechanism is transmitted, substantially as described. 70

4. The combination of rolls for holding the fabric under a proper tension while being measured with a graduation or register-imprinting mechanism made capable of movement to 80 and from the impression-roll for the purpose of engaging and disengaging the graduation or register imprinting device, substantially as described.

5. The combination of rolls for holding the 85 fabric under a proper tension while being measured and packaged with an intermediate impression-roll and a wheel, M, provided with graduation or register imprinting devices and journaled to a pivoted lever or frame, substantially as described. 90

6. The method of guarding against a false imprint of measure upon the fabric, which consists in automatically returning, by means substantially as described, the imprinting type-wheels to their zero-point between the completion of the registration of one piece of fabric and the commencement of the registration of the next piece, substantially as described. 95

7. The combination of the wheel M, made 100 capable of movement to or from an impression-roll and provided with graduating or registering devices, with the cam M² and cam-rib M³ upon the link-piece N², for automatically disengaging and re-engaging the graduating or 105 registering mechanism at the terminal registry of a web, substantially as described.

8. The combination of the wheel M, made 110 capable of an up-and-down movement and provided with graduation or register imprinting devices, with latch y, stop y², and driving-gears N N', for moving the wheel forward to complete the graduation or registration of one web, and then, upon raising the wheel M and disengaging the gears, allowing it to turn back 115 to the initial point for the graduation or registration of the succeeding web.

9. The combination of the wheel M, provided with graduating or registering devices with the spring Z, attached at one end to the 120 wheel M and at the opposite end to the frictionally-held wheel z, for permitting the wheel M to move forward indefinitely and serving to bring the graduating or registering mechanism back to its initial point for graduation or 125 registration, substantially as described.

10. The combination of the wheel M, provided with the geared register-imprinting type-wheels m' m², pawl w', and the spring q, for returning the type-wheels to their zero-point 130 upon the completion of the registration of each piece of fabric, substantially as described.

11. The combination of the geared type-wheels m' m^2 and pawl u' with a frictionally-held spring, q , for returning the wheels to their zero-point, and also permitting their indefinitely-continued forward movement, substantially as described. 60
12. The combination of the geared type-wheels m' m^2 , and the gear o^3 , shaft p' , and pivoted bearing r with the fixed cam t , operating to move the type-wheels successively forward, substantially as described. 65
13. The combination of the geared type-wheels m' m^2 and the fixed cam t with the sliding beveled cam v and rod r^3 , for effecting the engagement or disengagement of the gear o^3 , and thus controlling the action of the type-wheels, substantially as described. 70
14. The combination of the wheel M , provided with graduating or registering devices, and made capable of movement to and from an impression-roll, with the sliding beveled cam v , rod r^3 , and inclined link w , connected to a fixed portion, x , of the machine, and operating to effect the engagement and disengagement of the revolving type-wheels m' m^2 in accordance with the specific movement of the wheel M to or from the impression-roll, substantially as described. 75
15. The combination of the wheel M , provided with graduating or registering devices, with the compensating-gear N , arranged to turn the shaft m in a forward direction by means of the sliding catch l' , which also permits the gear to be moved freely in a backward direction after the stop y^2 upon the back of the wheel M has reached the top of the latch y , substantially as described. 80
16. The combination of the graduating or registering mechanism with the link L^5 and the spring shipper-rod O' , so that a movement of the graduating or registering mechanism from the impression-roll may cause the stoppage of the whole machine, substantially as described. 85
17. The combination of rolls for holding the fabric under tension while being measured and graduated or registered with a wheel, M , provided with graduation or register imprinting devices, and a guide, Y , placed in immediate proximity to the periphery of the wheel M and operating against the edge of the portion of the web included between the holding-rolls adjacent to the wheel M , substantially as described. 90
18. The frictioned tension-roll F' , for properly stretching the fabric, and the rolls J J' and J^2 J^3 , for holding the stretched fabric under tension while being measured and graduated or registered, in combination with a graduation or register imprinting mechanism located between the holding-rolls, substantially as described. 95
19. In a fabric measuring and packaging machine, the combination of a graduating or registering mechanism with a packaging mechanism, both, substantially as described, made to operate at an approximately-uniform tension upon the web, by means substantially as described, in order to prevent distortion of the imprinted measurement in the roll or bolt. 100
20. The combination of a packaging-mandrel and a frictional driving device, substantially as described, with an automatic friction-brake operating to preserve an approximately-uniform tension in the fabric throughout the rolled package, substantially as described. 105
21. The combination of the flat mandrel T , provided with the fixed spurs t^4 , with the loose sliding piece T' , provided with the spurs t^5 , for securely holding the packaging-board, substantially as described. 110
22. The combination of rolls for holding the fabric under a proper tension while being measured with means, substantially as described, for determining by comparison with a standard unit of measurement previously marked on the web the amount of stretch per linear unit to which the fabric is subjected in its passage into the machine. 115
23. The combination of rolls for holding the fabric under a proper tension while being measured with the flexible apron N^3 , removably attached to either end of the web, in order to insure the proper degree of tension at the initial or terminal points of measurement, substantially as described. 120
24. In a fabric-measuring machine, the combination of the link N^2 , for connecting the two webs, with an attached rib or device, M^3 , for causing the disengagement of the registering mechanism at the terminal registry of one web, and also the re-engagement of the same at the initial registry of the succeeding web, substantially as described. 125
25. The method of measuring elastic fabrics which consists in, first, determining the actual stretch or elongation produced in a certain length under a specific degree of tension, and then adjusting the movement of the mechanism for indicating, graduating, or registering the length of the web to compensate for the stretch or elongation so determined, substantially as described. 130
